HYDRAULIC STEERING GEAR FOR SHIPS

Pieter Jacobus Noordeman, Rotterdam,
Netherlands

Application October 3, 1951, Serial No. 249,423

7 Claims. (Cl. 114—146)

1

The present invention relates to hydraulic ship's steering gear of the kind wherein a hydraulic pump operates to deliver liquid under pressure to rams which actuate the rudder.

A hydraulic steering gear of this type has been proposed, for instance in the applicant's copending U. S. application Serial No. 765,060 of July 31, 1947, now issued as Patent 2,572,749, dated October 23, 1951, comprising in combination steering means for controlling the rudder of a vessel, a first hydraulic system associated with said steering means for moving the same in a first direction, a second hydraulic system operable for moving said steering means in an opposite direction, pumping means for supplying actuating fluid to either of said hydraulic systems, and yielding means interposed between said hydraulic systems and arranged, in response to accidental increase in pressure in either of said systems, to temporarily increase the volume capacity of the system in which the accidental increase occurs.

The object of the present invention is to provide an improved ship's steering gear of the kind referred to, which, on the one hand, is more simple and robust in construction and, on the other hand, is particularly adapted to be constructed in a manner to permit the hydraulic steering operation in emergency cases to be replaced by hand steering in accordance with the official requirements in this respect.

To attain this object the present invention provides a hydraulic steering mechanism for vessels comprising in combination, steering means associated with the rudder shaft for controlling the rudder of the vessel, a pair of hydraulic motor systems respectively pivotally connected to spaced points of said steering means, reversible pumping means for selectively supplying actuating fluid to either of said hydraulic motor systems, means for controlling said pumping means to effect movements of the rudder by either one or the other of said motor systems and said steering means, and means associated with said steering means for returning said pumping means to inoperative position after deflection of the rudder, said steering means being freely movable with respect to said rudder shaft and being connected thereto by elastic means resiliently transmitting the movements of said steering means to said rudder shaft and vice-versa.

Further characteristic features of my invention will be apparent from the hereinafter following description in which reference is had to the accompanying drawing illustrating a preferred

2

embodiment of my improved hydraulic ship's steering gear.

In this drawing:

Fig. 1 is a diagrammatic perspective view of such embodiment partially in section, certain parts being broken away for the sake of clearness.

Fig. 2 shows on an enlarged scale a bottom view of the steering means associated with the rudder shaft and comprising elastic shock absorbing means.

Fig. 3 is an enlarged sectional detail view of the means transmitting the movements of the hydraulic rams to said steering means.

Referring to Figures 1 and 2 of the drawing, 1 indicates a rudder shaft having freely rotatably mounted thereon a toothed quadrant 2 and carrying immediately underneath such quadrant a fixed arm 3 radially projecting from said shaft 1 and having at its free end connected thereto, respectively from below and above, and through the medium of trunnions 4 of which only one is shown in Fig. 2, the ends of two helical blade springs 5 and 6 respectively, the other ends of such springs being anchored to the under side of the quadrant by pins 7 and 8, secured at said quadrant in points on either side of the axis of the rudder shaft and equally spaced therefrom.

As shown in Fig. 1, the yoke-shaped body 9 of the quadrant 2 has formed therein two substantially radial grooves or slots 10 open at their outer end, each of said grooves containing a bar 11 of rectangular cross section held down in said groove by a clamp 12 bolted to the upper face of the body 9. The bars 11 have a sliding fit in said grooves 10 but are normally secured therein by a screw bolt 13 passing through said bar and screwed into the body 9 from above, so that, after unscrewing said screw bolts, the bars 11 may be lengthwise withdrawn from their grooves if so desired.

The portions of the bars 11 radially projecting from the grooves, each slidably pass through a diametrically extending passage 14 of rectangular cross section and formed in a circular block 15 with vertically extending axis and having coaxial trunnions 16 and 17, mounted for rotation in the respective lower and upper shanks 18, 19 of a forked cross head member 20, said shanks to this end each being formed in the manner of the marine end of a connecting rod as shown in detail in Fig. 3.

The heads 20 are each slidably mounted in four guide ways 21 joined together to form a box like frame 22 having horizontal flanges 23 for se-

curing said frame to a floor by bolts 24 as shown in Fig. 1. At their longitudinal side walls, said frames are each formed with a lengthwise extending slot 25 through which pass the projecting portions of the bars 11.

The forked cross heads 20 are each formed at the end of a ram 26 operating in a cylinder 27 formed integrally with the respective box-like frame 22, one end of said cylinders being connected by a conduit 28 to a reversible liquid supplying pump 29 of a type known per se, preferably a Hele-Shaw pump, with variable output, said pump being permanently driven by an electro motor 30 and comprising controlling means (not shown) actuated by a rod 31 which at 32 is pivotally connected to a lever 33. At 34 such lever is pivotally connected to a piston rod 35 of a piston 36 working in a cylinder 37 having pressure fluid supply conduits 38 and 39, such assembly constituting the well known telemotor to be operated from the bridge of the ship.

The opposite end of the two armed lever 33 is pivotally connected at 40 to a rod 41 which in turn is pivotally connected at 42 to a vertical projection 43 on the upper face of the body 9 of the toothed quadrant 2.

The mechanism so far described constitutes the novel hydraulic ship's steering gear of which the operation will be hereinafter described. Associated with such hydraulic steering gear I provide an emergency hand steering gear diagrammatically shown in Fig. 1 and comprising a steering wheel 44 mounted on a shaft 45 journaled in a pedestal 46, which is bolted to a floor at a level somewhat above that of the hydraulic steering gear.

The shaft 45 carries a worm 47 slidably but non-rotatably mounted thereon and being held in a substantially central position on said shaft by two helical springs 48 surrounding said shaft on either side of said worm and resting on the one hand against said worm and on the other hand against the inner face of the respective shaft bearings 49 and 50 respectively, so that the worm is capable of automatic resilient adjustment, all in a manner known per se.

The worm 47 meshes with a worm wheel 51 secured to the upper end of a vertical shaft 52, mounted for rotation in said pedestal 46 and passing through the floor to the level of the hydraulic steering gear, where it is journaled in a step bearing 53 secured to the floor on which the hydraulic steering gear is mounted at a point somewhat spaced from the toothed circumferential face of the quadrant 2. The vertical shaft 52 has a longitudinal key groove 54 formed therein for slidably but non-rotatably mounting on said shaft a pinion 55 adapted to mesh with the teeth 56 of said quadrant, said pinion normally being held in an elevated position in which it is disengaged from the teeth 56, by means of a forked hand lever 57 straddling the shaft 51 beneath said pinion 55 and being pivotally mounted at 58 in a fixed bracket 59. In the position shown, the free arm of the lever 57 having a handle 60, is held by a pin 61 passing through said arm and entering a hole 62 in an arm 63 projecting from said bracket. By removing the pin from this hole, the pinion 55 may be permitted to descend by gravity into its lower or operating position in which it is in mesh with the quadrant 2.

During normal operation, the elements of the steering gear are in the position shown in Fig. 1, i. e. the bars 11 are secured in place in their

grooves 10 by the screw bolts 13 and the pinion 55 is disengaged from the quadrant 2.

In this condition, by activating the telemotor 35, 36, the lever 33, in one or the other direction depending on the required adjustment of the rudder, is swung about the pivot 40 constituting the stationary fulcrum at this time—and thereby displaces the rod 31 to adjust the controlling means of the pump 29 for causing said pump to supply pressure liquid to one or the other of the ram cylinders 27, the other cylinder being evacuated. This causes the two rams 26 to be displaced in opposite directions, such movement, through the medium of the forked cross heads 20, blocks 15, and bars 11, being transformed into an angular movement of the quadrant 2 about the shaft 1 which movement through the helical springs 5 and 6 and arm 3 is resiliently transmitted to the rudder shaft 1 for actuating the rudder, the slidable and at the same time pivotal connection of the bars 11 with the cross heads 20 permitting such angular movement of the quadrant with respect to said heads. The angular displacement of the quadrant 2, through the medium of the rod 41 and the lever 33, causes the control element of the pump to be restored to neutral position.

If in any position of the rudder, the same is hit by a heavy sea, the resultant shock in the steering gear is immediately and adequately absorbed by the helical springs 5 and 6 thereby preventing breakage. In this respect it may be observed, that the transmission of the steering impulses to the rudder shaft through a freely rotatable quadrant having shock absorbing springs connecting such quadrant to a steering arm secured on said rudder shaft is known per se in the case of other ship's steering systems, so that the invention more particularly resides in the use of such quadrant in a hydraulic steering mechanism, whereby such hydraulic steering gear is raised to a scientifically justified construction.

More particularly the application of such quadrant enables the hydraulic steering gear to be provided with simple emergency hand steering means normally inoperative but adapted to be quickly and easily put in condition for replacing the hydraulic gear if for some reason or other such hydraulic gear is unfit for use.

To this end, the screw bolts 13, normally securing the bars 11 in position in the grooves 10, are removed enabling the bars to be lengthwise withdrawn from the grooves to thereby break the connection between the quadrant 2 and the heads 20 of the hydraulic rams. At the same time, by removing the pin 61 from the hole 62 the hand lever 57 is unlocked permitting the pinion 55 to descend and engage the teeth of the quadrant 2 so that now the quadrant and thereby the rudder shaft may be operated by hand through the steering wheel 44.

From the above it will be apparent that the present invention provides a simple and reliable hydraulic steering mechanism incorporating very robust shock absorbing means and complying in a very simple manner to the demand that hand steering means shall be provided to replace the hydraulic steering in case of emergencies.

While I have described my invention in detail in a certain embodiment, to enable it to be properly understood, it will be obvious for those skilled in the art, that various changes and mod-

ifications may be made therein, without departing from the scope of the appended claims.

What I claim is:

1. A hydraulic steering mechanism for vessels comprising in combination; steering means associated with the rudder shaft for controlling the rudder of the vessel, a pair of hydraulic motor systems respectively pivotally connected to spaced points of said steering means, reversible pumping means for selectively supplying actuating fluid to either of said hydraulic motor systems, means controlling said pumping means to effect movements of the rudder through either of said motor systems and said steering means, and means associated with said steering means operable to return said pumping means to inoperative position after deflection of the rudder, said steering means being rotatable with respect to said rudder shaft and elastic means connecting said steering means to said rudder shaft for resiliently transmitting the movements of said steering means to said rudder shaft and vice-versa.

2. A hydraulic steering mechanism as claimed in claim 1, wherein said steering means is rotatable about an axis coinciding with the axis of the rudder shaft.

3. A hydraulic steering mechanism as claimed in claim 1, wherein said steering means is in the form of a yoke, loosely mounted for rotation on said rudder shaft, an arm fixed to said rudder shaft, and said elastic means comprising helical springs connected between the opposite ends of said yoke and the outer end of said arm.

4. A hydraulic steering mechanism for vessels comprising in combination; steering means associated with the rudder shaft for controlling the rudder of the vessel, a pair of hydraulic motor systems respectively pivotally releasably connected to spaced points of said steering means, reversible pumping means for selectively supplying actuating fluid to either of said hydraulic motor systems, means controlling said pumping means to effect movements of the rudder through either of said motor systems and said steering means and means releasably associated with said steering means operable to return said pumping means to inoperative position after deflection of the rudder, said steering means being movable with respect to said rudder shaft and there being spring means resiliently urging the steering means and the rudder shaft toward a predetermined relative position for transmitting power therebetween, hand operated emergency steering gear being provided adapted to be put in condition for engaging said steering means for effect-

ing control of said rudder after said steering means has been disconnected from said hydraulic motor systems and said pump returning means.

5. A hydraulic steering mechanism as claimed in claim 4, wherein said steering means is in the form of a toothed quadrant, mounted for rotation on said rudder shaft, said hand operated emergency steering gear comprising a pinion normally disengaged from said quadrant and adapted to be engaged therewith at will.

6. A hydraulic steering mechanism as claimed in claim 4, characterised by said steering means being provided with oppositely directed rod-like projections, cross heads actuated by said hydraulic motor systems in which said projections are mounted for combined swinging and sliding movement, said projections being connected to said steering means by means adapted to be disengaged at will to disconnect said steering means from said hydraulic motor systems.

7. A hydraulic steering mechanism comprising in combination a pair of hydraulic motor systems, reversible pumping means for selectively supplying actuating fluid to either of said motor sys-

tems, control means controlling said pumping means, crossheads arranged to move in a path on either side of the rudder shaft and respec-

tively connected to said hydraulic motor systems to be actuated thereby, a toothed quadrant mounted for rotation on said rudder shaft and having oppositely directed detachable rod-like projections mounted for combined swinging and sliding movement in said cross heads, disengage-

able means connecting said projections to said quadrant, a steering arm fixed on said rudder shaft and projecting radially therefrom, springs connecting said arm with points of said quadrant located on either side of said rudder shaft, and hand operated emergency steering gear, com-

prising a pinion normally disengaged from said toothed quadrant but adapted to be engaged therewith at will for effecting control of the rudder after said rod-like projections have been disconnected from said toothed quadrant.
